UNITED STATES PATENT OFFICE.

THOMAS DORWIN, OF CHICAGO, ILLINOIS.

DESIGN FOR A MEDALLION OR MEDAL.

SPECIFICATION forming part of Design No. 21,185, dated December 1, 1891.

Application filed October 12, 1891. Serial No. 408,518. Term of patent 3½ years.

To all whom it may concern:

Be it known that I, THOMAS DORWIN, a citizen of the United States, residing in Chicago, county of Cook, and State of Illinois, have 5 invented and produced a new and original Design for a Medallion or Medal, of which the following is a specification, reference being had to the accompanying drawings.

My design is intended particularly for use 10 in connection with the Columbian World's Fair at Chicago; and it consists of two separate features intended for the obverse and reverse sides of the medallion or medal representing historical scenes associated with said 15 exposition.

Figure I is a scene representing the landing of Columbus in America in 1492, surrounded by a space inclosed by double circles forming a panel adapted to receive the words "Land-

ing of Columbus in America, 1492," or other 20 suitable inscription; Fig. II, a scene representing a bird's-eye view of the exposition grounds and buildings and the surroundings as the same will appear when completed. This is also surrounded by a space inclosed by 25 double circles forming a panel adapted to receive the words "World's Columbian Exposition, Chicago, 1893," or other suitable inscription.

What I claim, and desire to secure by Letters Patent, is—

The design for a medallion or medal, as herein described and shown.

THOMAS DORWIN.
